UNITED STATES PATENT OFFICE

168,308

BABY CARRIAGE BODY

Michael Lewin, New York, N. Y.

Application June 19, 1952, Serial No. 20,265

Term of patent 14 years

(Cl. D14—14)

To all whom it may concern:

Be it known that Michael Lewin, stateless, residing at New York, in the county of New York and State of New York, has invented a new, original, and ornamental Design for a Baby Carriage Body, of which the following is a specification, reference being had to the accompanying drawing, forming part thereof.

In the drawing:

Fig. 1 is a perspective view taken from the front and one side of a baby carriage body, showing my new design;

Fig. 2 is a rear elevational view taken from the left of Fig. 1;

Fig. 3 is a bottom perspective view thereof; and

Fig. 4 is a perspective view thereof, showing the bottom, rear, and one side.

The other side not shown in the drawing is like the side shown therein.

The compartment lid is shown in open position in Figs. 1, 2 and 4, and in closed position in Fig. 3.

I claim:

The ornamental design for a baby carriage body, substantially as shown and described.

MICHAEL LEWIN.
